United States Patent Office

Des. 212,333
Patented Oct. 1, 1968

212,333

FIGURINE

Joseph A. Del Porto, 5000 C St.,
Sacramento, Calif. 95819

Filed Sept. 1, 1967, Ser. No. 8,470

Term of patent 14 years

(Cl. D29—23)

FIG. 1.

FIG. 2.

FIG. 3.

The broken lines represent a conventional base.

I claim:

The ornamental design for a figurine, substantially as shown and described.
